(57) **CLAIM**

The ornamental design for a vented tip, as shown and described.

DESCRIPTION

FIG. 1 is a front left bottom perspective view of a vented tip showing the new design;

FIG. 2 is a top, front, right perspective view thereof;

FIG. 3 is a left side view thereof;

FIG. 4 is a right side view thereof;

FIG. 5 is front view thereof;

FIG. 6 is a back view thereof;

FIG. 7 is a bottom plan view thereof; and,

FIG. 8 is a top plan view thereof.

The even-length broken lines shown in the drawings illustrate portions of the vented tip that form no part of the claimed design.
